Application April 13, 1953, Serial No. 24,472

Term of patent 7 years

(Cl. D87—3)

To all whom it may concern:

Be it known that I, Alexander Ross, have invented a new, original, and ornamental Design for a Combination Billfold and Coin Holder, of which the following is a specification, reference being had to the accompanying drawing, forming a part hereof.

Fig. 1 is a perspective view of one side of the combination billfold and coin holder embodying my new design;

Fig. 2 is a rear view of the same showing the other side of the device; and

Fig. 3 is a front elevation of the device with the coin holder in open position.

I claim:

The ornamental design for a combination billfold and coin holder, as shown.
